Patented Dec. 20, 1927.

1,653,450

UNITED STATES PATENT OFFICE.

JOSEPH F. CARROLL, OF DENVER, COLORADO.

TEMPLATE.

Application filed February 9, 1927. Serial No. 166,980.

My invention relates to and has for its purpose the provision of a template, stencil, pattern or guide possessing certain geometrical characteristics by which it is possible 5 to form singly various characters, such as the several letters of the alphabet, the several digit numerals, and the punctuation marks used in writing or printing.

Further, it is a purpose of my invention 10 to provide a template the outlines of which are part of a geometrical figure or character as a whole, and of any letter, numeral or mark formed therein so that the latter will appear proportionately correct to the 15 eye and to enable the eye to quickly select a group of outlines that define the borders of any letter, numeral or mark.

I will describe only two forms of template embodying my invention, and will 20 then point out the novel features thereof in claims.

In the accompanying drawings,

Figure 1 is a view showing in front elevation one form of template embodying my 25 invention;

Figure 2 is a vertical sectional view taken on the line 2—2 of Figure 1;

Figures 3 and 4 are views similar to Figure 1, but on a reduced scale and showing 30 one manner in which the template can be employed to form numerals and letters, respectively;

Figure 5 is a view similar to Figure 1 showing another form of template embodying 35 my invention;

Figure 6 is a sectional view taken on the line 6—6 of Figure 5;

Figures 7 and 8 are views similar to Figures 3 and 4, showing one manner in which 40 the template of Figure 5 can be employed to form letters and numerals, respectively.

My invention, in the embodiment shown in Figure 1, comprises a template made up of a plurality of partitions constructed of 45 any suitable rigid material and permanently secured to each other to maintain the definite form shown. The partitions may be constructed of strips of metal welded to each other or they may be all cast in a single operation.

In the present instance, the template is made up of two polygonal partitions 15 and 16 arranged concentrically. A pair of straight-line partitions 17 extend transversely of the outer polygonal partition 15 in a manner to intersect the inner polygonal

partition 16. A second pair of straight-line partitions 18 are arranged at right angles to the partitions 17, while intersecting the latter partitions adjacent their ends respectively, are relatively short straight-line partitions 19. A pair of partitions 20 shorter in length than the partitions 19 connect the partitions 18 at spaced points between the partitions 17. Extending from the opposite ends of the partitions 20, are short diagonal partitions 21, and long diagonal partitions 22. The partitions 21 are connected with the inner polygonal partition 16 and at the same 70 points as the inner ends of other diagonal partitions 23, the latter extending to the outer polygonal partition 15 and are connected therewith at points corresponding to the ends of the partitions 19. The diagonal 75 partitions 22 are in converging relation to each other and terminate at a common point on the inner polygonal partition 16. From this point other diagonal partitions 24 extend from the inner polygonal partition 16 80 to the outer circular partition at points corresponding to the ends of the straight-line partition 17.

Partitions arranged as described provide intervening openings in which or behind 85 which elements are placed such as blocks of solid or transparent material colored or uncolored or sheets of similar material. In fact, anything capable of completely filling or spanning any desired groups of openings 90 to form any desired letter, numeral or punctuation mark. In practice, the elements 25 are of a color different from that of the color of the edges of the partition, the latter being also colored as indicated in the drawing and 95 preferably of a darker color than the color of the elements. In this manner, the character formed within the template is clearly discernible and distinguishable from the template, the latter producing a highly artistic 100 and filigreed background. The edges of the partitions define the outlines or boundaries of a character or a part of the character as a whole, and being of a darker color produce a stenciled or cut effect, so that the character 105 appears proportionately correct to the eye.

In Figures 5 to 8, inclusive, I have shown another form of template embodying my invention which is identical to the form shown in Figure 1, with the exception that the partitions 19 are extended beyond the outer polygonal partition 15, as indicated at 26.

These partition extensions are connected with the outer polygonal partition 15 at their outer ends by short straight line partitions 27 disposed at right angles thereto and tangent to the polygonal partition 15. Similarly, this form of my invention is adapted to receive elements 25 in or at the rear side of the openings formed by the partitions within the outer polygonal partition, as well as the openings formed by the partitions 26 and 27, in order to produce the numerals or letters as illustrated in Figures 7 and 8, or punctuation marks. As in the first form, the elements are adapted to be colored and the exposed edges of the partitions of a darker color to produce the same effect as described in connection with the template shown in Figure 1.

In either form of my invention, the template can be used as described to form various characters or can be used as a stencil for the printing or painting of characters on surfaces as in the making of signs. Further, they may be employed as educational puzzles for children in teaching the different characters used in writing.

Although I have herein shown and described only two forms of template embodying my invention, it is to be understood that various changes and modifications may be made therein without departing from the spirit of the invention and the spirit and scope of the appended claims.

I claim as my invention:

1. A template comprising two polygonal partitions concentrically arranged, two

straight-line partitions extending inwardly from the outer polygonal partition and intersecting the inner polygonal partition, a second pair of straight-line partitions extended inwardly from the outer polygonal partition and intersecting the inner polygonal partition, the second pair of partitions intersecting the first pair at right angles, a third pair of straight-line partitions intersecting the second pair adjacent the ends of the latter and connected at their ends to the outer polygonal partition, a fourth pair of straight-line partitions spanning the second pair of partitions at points between the first pair of partitions, a pair of relatively short diagonal partitions at the ends of each of the partitions of the fourth pair, a pair of relatively long diagonal partitions at the ends of each of the partitions of the fourth pair, the first mentioned diagonal partitions being arranged in divergent relation to the second mentioned diagonal partitions and connected with the inner polygonal partition, and diagonal partitions extending from the ends of the first and second mentioned diagonal partitions to the outer polygonal partition.

2. A template as embodied in claim 1 wherein the straight-line partitions of the third pair are extended beyond the outer polygonal partition with short straight-line partitions connecting the ends of said partitions to the outer polygonal partition at an angle thereto.

JOSEPH F. CARROLL.
